UNITED STATES PATENT OFFICE.

GEORGE N. TOMPKINS, OF CROTON ON HUDSON, NEW YORK.

FASTENER.

1,071,825.

Specification of Letters Patent.

Patented Sept. 2, 1913.

Application filed April 12, 1912. Serial No. 690,328.

To all whom it may concern:

Be it known that I, GEORGE N. TOMPKINS, a citizen of the United States, and a resident of Croton on Hudson, in the county of West-
5 chester and State of New York, have invented a new and Improved Fastener, of which the following is a full, clear, and exact description.

My invention relates to fasteners, and it
10 has for its object to provide one with a member in which three radiating cuts are made, the edges of the member at one of the cuts being rolled back to form an opening, in which a pin may be disposed.

15 Additional objects of the invention will appear in the following complete specification, in which the preferred form of the invention is disclosed.

In the drawings similar characters of reference indicate corresponding parts in all the views, in which—

Figure 1 is a plan view, showing how the three radiating cuts are made; Fig. 2 is a view on the same plane, after the edges of
25 the plate at one of the cuts are rolled back, to form the fastener; Fig. 3 is a sectional view on the line 3—3 of Fig. 2, with the pin disposed in position in the fastener; and Fig. 4 is a sectional view on the line 4—4 of
30 Fig. 2.

By referring to the drawings it will be seen that a plate 5 is provided, in which cuts 6, 7 and 8 are made, these cuts radiating from a central point 9. The edges 10 at the
35 cut 6 are then rolled back with the edges 11, rolled longitudinally of the cuts 7 and 8, to form the fastener shown in Figs. 2, 3 and 4 of the drawings.

The fastener having been constructed as
40 stated, another plate 12 having a pin 13, secured thereto, is disposed under the plate 5, so that the pin 13 may project through the opening 14, adjacent the central point 9, the pin 13 being locked relatively to the plate
45 5 when it is moved to the left, the rolled portions 10 of the plate engaging the head 15 to prevent the pin 13 from becoming free from the plate 5 until the pin is again moved to the end adjacent the central point 9.

50 This fastener can be manufactured very cheaply and it is exceedingly strong and durable.

It will be understood that as the edges 10 of the plate where they meet the edges 11 are

disposed farther away from the plane of the 55 plate than the edges 10 at the left of the cut 6, the pin 13 will travel to the left of the cut, and away from the central point 9 in the plate 5, when there is a strain on the pin 13 away from the plate 5. It will also be seen 60 that the point 9 will serve to prevent the pin 13 from traveling in or between the cuts 7 and 8, and also to the right beyond the highest portions at the right of the rolled edges 10. 65

As the plate 5 is preferably of resilient metal, the rolled edges 10 may be sprung away from each other to permit the passage of a head on a pin, which is greater in diameter than the normal distance between the 70 two rolled edges 10.

Having thus described my invention I claim as new, and desire to secure by Letters Patent:

1. In a fastener, a metal plate in which 75 three cuts are made radiating from a point, triangular portions of the metal plate being rolled back from one of the cuts, and longitudinally of the other cuts.

2. In a fastener, a metal plate in which 80 three cuts are made radiating from a point, triangular portions of the metal plate being rolled back from one of the cuts, and longitudinally of the other cuts, and a pin adapted to be disposed in the opening made by the 85 rolled portions of the metal plate, and a head on the pin for engaging the rolled portions of the plate.

3. In a fastener, a resilient plate, in which 90 three cuts are made, radiating from a point, the edges of the resilient plate being rolled back from a point at the outer end of one of the cuts, and longitudinally of the other cuts, to form a triangular opening having as its apex the second-mentioned point. 95

4. In a fastener, a resilient metal plate, in which two cuts are made radiating from a point, a triangular portion of the resilient metal plate being rolled back from one of the cuts, and longitudinally of the other cut, 100 to form a triangular opening.

In testimony whereof I have signed my name to this specification in the presence of two subscribing witnesses.

GEORGE N. TOMPKINS.
